(**) Term: **14 Years**

(57) **CLAIM**

The ornamental design for a portion of an electronic computer, as shown and described.

DESCRIPTION

FIG. 1 is a top, front and right side perspective view of a portion of an electronic computer showing my new design, FIG. 2 is a front elevational view thereof, FIG. 3 is a rear elevational view thereof, FIG. 4 is a left side elevational view thereof, FIG. 5 is a right side elevational view thereof, FIG. 6 is a top plan view thereof, FIG. 7 is a bottom plan view thereof, FIG. 8 is a plan view with a display being turned to a position from a home position thereof; and, FIG. 9 is an enlarged perspective view showing the portion of an electronic computer with the display being omitted. The broken line showing of the remainder of the electronic computer is for illustrative purposes only and does not form any part of the design.
